UNITED STATES PATENT OFFICE.

GEORGE H. LUTZ, OF PHILADELPHIA, PENNSYLVANIA.

COVER-OPERATING MECHANISM FOR GARBAGE, ASH WAGONS, AND THE LIKE.

Application filed November 30, 1925. Serial No. 72,094.

The present method of operating covers on garbage or ash wagons, which may weigh approximately one hundred pounds or more, is to raise or actuate the cover by lifting it 5 at one end only which results in the sagging and constant weakening of the covers, even though they have been reinforced by braces of various characters.

My invention is designed to obviate these 10 objectionable features and consists of a novel fastening of the cover to a shaft, which when turned by suitable means will raise the cover at all points alike, thereby distributing the strain equally over the entire surface 15 of the cover, thus prolonging the life of the latter, and in addition greatly minimizing the labor of actuating the same.

On windy days it is objectionable to expose a large opening to the interior of an ash 20 wagon or the like and therefore the covers may be sub-divided and each of the sub-divisions may be opened or operated independently according to requirements by my novel mechanism to be hereafter referred to.

By my invention I have devised a novel 25 means for raising and lowering these covers with a minimum expenditure of labor on the part of the operator thereby making the operation more efficient and with less loss of time than heretofore.

To the above end my invention consists of 30 a novel construction of frame work, and a novel manner of mounting and actuating the sectional covers employed, which can be actuated from either end of the wagon, by the novel mechanism hereafter referred to.

For the purpose of illustrating my invention I have shown in the accompanying drawings several forms thereof which are at 35 present preferred by me, since the same have been found in practice to give satisfactory and reliable results; although it is to be understood that the various instrumentalities of which my invention consists can be variously arranged and organized and that my invention is not limited to the precise arrangement and organization of the instrumentalities as herein shown and described.

Figure 1, represents a side elevation of a 40 cover actuating mechanism and covers therefor embodying my invention, the wagon to which the same is applicable being shown in dotted lines.

Figure 2, represents on an enlarged scale 55 an end view of Figure 1, the covers being shown closed.

Figure 3, represents a partial front elevation of a modification.

Figure 4, represents a side elevation of another embodiment of my invention.

Figure 5, represents a front view of a cover in detached position.

Figure 6, represents a perspective view 65 of another form of cover.

In carrying out my invention, I mount upon each end of a suitable wagon, tractor, or the like 1, the end A-frames 2, composed of upwardly converging beams 3, which may be channels, I-beams, angle beams or any 70 other suitable shape in section, which have their lower ends suitably supported and are tied together at their upper ends by the gussets 4. The longitudinally extending upper tie piece 5, which connects the upper portions of the two A-frames 2 may be a channel or I beam or of any other suitable shape and in the present instance I have shown an I-beam employed. The ends of the bottom flange 6 of the I-beam 5 rest upon the tops of 75 the gussets 4 and are secured thereto in any suitable manner. 7 designates brackets which are oppositely located at the ends of the I-beam 5 and have their feet or flanges 8 secured to the vertical web of said I-beam by bolts, rivets or the like 9. The outer portions 10 of the brackets 7 form bearings for the outer ends of the pairs of the longitudinally extending shafts 11. I preferably employ two shafts 11 at each side of the I-beam 80 and the inner juxtaposed ends 12 and 13 of said shafts 11 have their bearings in the spacers 14 which are secured to the middle portion of the I-beam 5 on each side thereof.

By this construction instead of a single shaft 95 on each side which is liable to sag or bind, I employ two relatively short shafts, as seen in Fig. 1 whose ends are effectively supported, and I also employ the intermediate bearings 11^x seen in Fig. 1, which prevent the 100 central portions of the shafts 11 from sagging.

15 designates arms, whose inner ends are pinned at 16, to the outer ends of the shafts 11, so as to move in unison therewith. In the outer ends of said arms 15 are the slots 17 through which pass the pins or bolts 18 which are mounted in the upper ends of the 105

lifting or actuating racks 19, whose lower inner edges are provided with the rack teeth 20. The lower ends 21 of the lifting racks pass through and are guided in the bottom 5 horizontal wall 22 of the vertical plate 23.

24 designates collars fastened on the lower portions of the lifting racks, and between said collars and the walls 22 are interposed the cushioning springs 25, whereby it will 10 be seen that any injurious shock or jar will be prevented by said springs upon the descent of the rack bars. The upper intermediate portions of the lifting racks 19 are guided by their contact against the upper 15 horizontal bar 26 and the lower horizontal bar 27, said bars being riveted or otherwise secured to the members 3 of the end A-frames 2. The outer ends of the lower bar 27 carry the laterally extending pins 28, which serve 20 to arrest the outer movement of the hand levers 29, whose lower ends are rigidly mounted upon the shafts 30 each of which carries a ratchet wheel 31, which is fast thereon, said ratchet wheel being engaged by the locking 25 pawl 32, there being also an actuating pawl 33 mounted on the handle or lever 29. 34 designates the rack pinions which are fast on the shafts 30 and are in mesh with the racks 20 for actuating the latter. 35 designates a pair of covers arranged on each side 30 of the top of the device, said covers, if desired, having their top portions cut out as shown at 36 and provided with the supporting lugs or members, 37, which are pinned 35 at 38 to the shaft 11, so that said covers and shafts move in unison. I preferably employ a plurality of covers two being shown in Fig. 1 on each side of the wagon and four being employed in the entire construction, it being apparent that any desired 40 number of these sectional covers may be employed for each of the shafts 11. It will be evident that the covers 36 can be made out of sheet metal or if desired they may be made of a suitable light or skeleton frame work 39, comprising the ends 40, joined by the slats 41 and covered with canvas or other material 42 as seen in Figure 6, it being only essential that the cover sections 45 35 have their upper portions pinned or otherwise secured to the shafts 11, so that both ends of the covers can be actuated simultaneously up or down. In the construction seen in Figures 1 to 3, it will be 50 apparent that on each side of the beam 5, is located a pair of the cover actuating shafts 11, having their inner and outer ends and intermediate portions mounted in suitable bearings. Each shaft 11 has a cover section 55 35 secured fast thereto, so that when the arms 15 at either end of the wagon are rocked by the actuation of the racks 20, the covers will be actuated in the desired direction. There may be two of the manually 60 operated levers 29 at each end of the wagon 65

so that whichever cover it is desired to operate can be readily actuated from either end of the wagon by rocking the levers 29, whereupon the actuating pawl 33 actuates the ratchet wheel 31, the shaft 30, the pinion 34 and the coacting rack 20, the pawl 32 serving as the locking pawl. It will be evident that the ratchet teeth may be turned in a direction opposite to that seen in Figure 2 as in Figure 3. 70

By employing the cover construction seen in Figure 6, a very light and easily operated construction is attained, and by employing the sectional cover construction seen in Figure 1, either the front or rear half of 75 the top of the wagon at either side or end is readily accessible. In some instances it may be desirable to employ four cover sections instead of two on each side of the wagon, in which case the construction seen in Figure 4 is used, Figure 4 representing one half of the side of the wagon. The end A-frames 2 having the upwardly converging beams 3 and the top longitudinal beam 5 and the spacers 14 and the brackets 7, are the same as already described. The shaft 43 in Figure 4 corresponds to the shaft 11 already described, except that its left hand end is extended through the left hand bracket 7, its right hand end having its bearing in the spacer 14. The arm 44 is pinned to the outer end of the shaft 43, and corresponds to the arm 15 already described, and is actuated by the pawl and ratchet mechanism 45, which is the same as that seen in Figure 3. The inner cover section 46 has its upper lugs or arms 47, pinned at 48 to the shaft 43, so that upon actuating said shaft the inner cover section 46 will be raised or lowered as desired. The outer cover section 49 has its upper arms 50 pinned at 51 to a sleeve or tube 52 which is freely rotatable upon the shaft 43. 53 designates an arm which is pinned to the tube 52 at the point 54 and said arm is pivotally connected at 55 to the rack 56, which is operated by the ratchet mechanism 57 which is the same as already described or as seen in Figures 2 and 3. Thus on windy days, when it is desired to expose only a small portion of the 100 top of the ash cart, it will be seen that the construction seen in Figure 4 may be employed. In all the embodiments of my invention, it will be seen that the upper end portions of the covers are connected at two points with their actuating shaft, so that the weight of the covers is properly supported and there is no strain or distortion thereof 105 during their actuation. 110

It will now be apparent that I have devised a novel and useful construction for cover operating mechanism for garbage, ash wagons and the like, which embodies the features of advantage enumerated as desirable in the statement of the invention and 115 120 125 130 135

the above description and while I have in the present instance shown and described the preferred embodiments thereof which have been found in practice to give satisfactory 5 and reliable results, it is to be understood that the same are susceptible of modification in various particulars without departing from the spirit or scope of the invention or sacrificing any of its advantages.

10 Having thus described my invention, what I claim as new and desire to secure by Letters Patent, is:—

1. In a device of the character stated a plurality of longitudinally extending aligning shafts supported above said wagon, bearings for the outer ends of said shafts, intermediate bearings for the inner juxtaposed aligning ends of said shafts sectional covers having their upper edge portions secured 20 fast to said shafts so as to operate in unison therewith, whereby distortion of said covers is prevented, slotted rack arms on the ends of said shafts, upright rack bars having their upper ends pivotally connected to said rack 25 arms.

2. In a device of the character stated a plurality of longitudinally extending aligning shafts supported above said wagon, bearings for the outer ends of said shafts 30 intermediate bearings for the inner juxtaposed aligning ends of said shafts sectional covers having their upper edge portions secured fast to said shafts so as to operate in unison therewith, whereby distortion of said covers is prevented in combination with means for actuating each of 35 said shafts and covers comprising upright racks having pivotal connections to the outer ends of said shafts, pawl and ratchet mechanism for said racks, and cushioning devices 40 for the lower ends of said racks.

3. In a device of the character stated, end supporting frames, a longitudinally extending beam connecting said frames, a plurality 45 of shafts on each side of said beam, brackets secured to said beam, in which said shafts have their bearings, a plurality of cover sections having their upper edge portions secured fast to said shafts, upright racks 50 pivotally connected to the outer ends of said shafts, and manually operated pawl and ratchet mechanism for actuating said racks.

4. In a device of the character stated, end supporting frames, a longitudinally extending beam having its ends mounted on said

frames, a plurality of longitudinally extending shafts on each side of said beam, brackets secured to the outer ends of said beam in which the outer ends of said shafts have their bearings, intermediate supports carried by said beam in which the inner juxtaposed inner ends of said shafts have their bearings, a plurality of cover sections, one for each shaft having their upper edge portions secured to said shafts so as to operate in unison therewith, upright racks having pivotal connections to said shafts, and pawl and ratchet mechanism for actuating said racks. 60

5. In a device of the character stated, for a wagon, a plurality of longitudinally extending aligning shafts supported above said wagon, bearings for the outer ends of said shafts, intermediate bearings for the inner juxtaposed aligning ends of said shafts sectional covers having their upper 70 edge portions secured fast to said shafts so as to operate in unison therewith, whereby distortion of said covers is prevented, said covers being composed of end pieces connecting members and a covering material 75 for the latter, arms attached to the outer ends of said shafts, upright racks pivotally attached to said arms, pawl and ratchet mechanisms for actuating said racks, and cushioning mechanisms for the lower ends 80 of said racks.

6. In a device of the character stated a plurality of sectional covers for each side of the wagon top, independent shafts for said covers, each of the latter having their 85 upper edge portions attached to its respective shaft, arms attached to said shafts, upright rack bars having their upper ends pivotally attached to said arms, and pawl and ratchet mechanism for operating each 90 of said rack bars.

7. In a device of the character stated a plurality of sectional covers for each side of the wagon top, independent shafts for said covers, each of the latter having their 100 upper edge portions attached to its respective shaft, slotted arms attached to said shafts, upright rack bars having their upper ends pivotally connected to the slots in said arms, and a pair of manually operated pawl 105 and ratchet mechanisms at each end of said wagon for effecting the independent operation of each of said shafts and the cover fast thereon.

GEORGE H. LUTZ.
